[57] ABSTRACT

A means and apparatus for digitally controlling the reciprocating motion of a yarn traverse guide using pulse signals for the purpose of winding the filaments on bobbins to a definite form is disclosed. A pulse signal is generated in proportion to the distance of the movement of the traverse guide, said pulse signal starting to be counted as said traverse guide passes the reference position near the center of the bobbin, direction of the movement of the traverse guide being reversed as the number of pulses counted reaches the setpoint value, and the traverse guide being controlled to gradually shorten its stroke as said setpoint value is decreased sequentially.

METHOD AND APPARATUS FOR CONTROLLING THE TRAVERSE MEMBERS OF A WINDER

BACKGROUND OF THE INVENTION

1. Field of the Invention

This invention relates to a method and apparatus for controlling traverse devices used for winding filaments, especially used for winders for winding synthetic filaments on bobbins.

2. Description of the Prior Art

In order to form stable filament layers on bobbin yarn traverse guides or bobbin support members, it is required to perform the reciprocating motion by gradually decreasing the length, i.e., in parallel winding manner.

Traverse members heretofore in use, such as yarn traverse guides and bobbin support members have been installed on a traverse rod or traverse belt driven by a hydraulic cylinder or motor, and the control of stroke has been performed by a pattern plate. Movement of the pattern plate which moves together with the traverse member is detected by means of a photo-electric system; interruption of light rays by the pattern plate causes the electromagnetic valve or relay to operate so that the moving direction of the traverse member is reversed, while slow movement of the pattern plate perpendicular to the traverse direction controls the traverse member so that the range of stroke gets gradually shorter (see U.S. Pat. No. 1,077,651).

However, the modern trend toward higher winding speeds has resulted in increased centrifugal force which acts to the filament layer, presenting the possibility of slough off. To prevent this it became necessary to accurately control the form of package, i.e., to control the traverse member more accurately. Also where a multi-spindle spindrawing machine is used, it is desirable to control the traverse mechanism independently for each or for definite numbers of spindles for reducing the required manpower for replacing bobbins as well as for reducing the amount of waste threads produced. The conventional control devices, however, necessitate a mechanical setup such as a bulky pattern plate which is not suited for independent attachment to individual spindles.

SUMMARY OF THE INVENTION

This invention has succeeded in providing a method and apparatus for controlling the traverse members of the winder eliminating the abovementioned drawbacks.

It is an object of this invention to provide a method and apparatus for controlling the traverse members which is capable of forming accurately the package of filament layers to a desired form.

It is another object of this invention to provide a method and apparatus for digitally controlling the stroke of traverse members using a pulse signal generated in proportion to the distance of the movement of the traverse member, without using a pattern plate.

It is a further object of this invention to provide a small and precision control device.

It is yet another object of this invention to provide a control device which allows the setting of accurate winding time.

According to this invention, there is provided a method comprising, producing stroke pulses everytime the traverse member moves a predetermined distance, counting the number of said pulses from the time at

which said traverse member has passed a reference position, reversing said traverse member when the number of pulses counted has reached a setpoint value, and reducing said setpoint values sequentially so that the stroke of said traverse member is reduced gradually, maintaining a reciprocating motion in parallel winding.

According to this invention, there is provided a control apparatus comprising, a means for producing stroke pulses everytime the traverse member moves a predetermined distance, a means for producing a reference position signal when said traverse member has passed a predetermined reference position, a first counter circuit which starts to count said stroke pulses from the time at which said reference position signal is produced thereby increasing the counted values one by one, a second counter circuit which counts the reversing of said traverse member and reduces the counted values one by one, a coincidence discriminating circuit which produces a coincidence signal when the counted values of said first and second counter circuits coincide with each other, and a circuit which upon receipt of said coincidence signal causes said traverse member to be reversed, thereby the stroke of said traverse member is shortened by a definite length for every reversed.

According to this invention, there is provided a control apparatus comprising, a means for producing stroke pulses everytime the traverse member moves a predetermined distance, a means for producing a reference position signal when said traverse member has passed a predetermined reference position, a first counter circuit which starts to count said stroke pulse from the time at which said reference position signal is produced and increases the counted values one by one, a circuit which produces a control signal when the counted value of said first counter circuit reached a set-point value, a circuit which upon receipt of said control signal causes said traverse member to be reversed, a second counter circuit which counts the reversing of said traverse member to increase the counted values one by one, and a coincidence discriminating circuit which produces a coincidence signal when the counted values of said first and second counter circuits coincide, thereby when said coincidence signal is produced, said first counter circuit stops the counting of said stroke pulse, thereby reducing the stroke of said traverse member by a definite length for every reversed.

According to this invention, there is provided a control apparatus comprising, a means for producing stroke pulses everytime the traverse member moves a predetermined distance, a means for producing a reference position signal when said traverse member has passed a predetermined reference position, a first counter circuit which starts to count said stroke pulse from the time at which said reference position signal is produced and increases the counted values one by one, a pulse generating circuit for producing clock pulses, a second counter circuit which counts said clock pulse and reduces one by one the counted values which has been preset, a coincidence discriminating circuit which produces a coincidence signal when the counted values of said first and second counter circuits coincide with each other, and a circuit which upon receipt of said coincidence signal causes said traverse member to be reversed, so that the stroke of said traverse member is shortened by a definite length for every production of said clock pulse.

According to this invention, there is provided a control apparatus comprising, a means for producing a stroke pulses everytime the traverse member moves a predetermined distance, a means for producing a reference position signal when said traverse member has passed a predetermined reference position, a first counter circuit which starts to count said stroke pulse from the time at which said reference position signal is produced and increases the counted values one by one, a circuit which produces a control signal when the counted value of said first counter circuit has reached a setpoint value, a circuit which upon receipt of said control signal causes said traverse member to be reversed, a pulse generating circuit for producing clock pulses, a second counter circuit which counts said clock pulse and increases the counted values one by one, and a coincidence discriminating circuit which produces a coincidence signal when the counted values of said first and second counter circuits coincide, so that when said coincidence signal is produced, said first counter circuit stops the counting of said stroke pulse, thereby reducing the stroke of said traverse member by a definite length for very production of clock pulse.

The embodiments of this invention which is applied to the traverse mechanism for yarn traverse guide are illustrated below with reference to the accompanying drawings.

In the drawings,

FIG. 1 shows the traverse mechanism for filament guide means in accordance with this invention.

FIG. 2 is a block diagram showing a drive mechanism for the traverse member of FIG. 1,

FIG. 3 is a block diagram showing an example of the control device for the traverse member in a manner which reduce the upper limit value for every reversed of the traverse member in order to decrease the stroke,

FIG. 4 is a time chart to illustrate the operation of the control device of FIG. 3,

FIG. 5 shows counter circuits and a coincidence discriminating circuit in the control device of FIG. 3,

FIG. 6 is a block diagram showing another example of the control device for the traverse member in a manner which increases the initial value for every reversed of the traverse member in order to reduce the stroke,

FIG. 7 is a time chart to illustrate the operation of the control device of FIG. 6,

FIG. 8 shows counter circuits and a coincidence discriminating circuit in the control circuit of FIG. 6,

FIG. 9 is a block diagram showing a further embodiment of the control device for the traverse members in a manner which reduces the upper limit values by means of clock pulses in order to decrease the stroke.

FIG. 10 is a time chart to illustrate the operation of the control device of FIG. 9,

FIG. 11 is a block diagram showing still another example of the control device of the traverse member in a manner which increase the initial value by means of clock pulses in order to decrease the stroke, and

FIG. 12 is a time chart to illustrate the operation of the control device of FIG. 11.

Referring to FIG. 1, filament 1 fed from the filament supplying mechanism (not shown) is taken up on bobbin 3 and inserted into spindle 15 driven by belt 16, through traverse guide 2, to form package 4. Traverse guide 2 is attached to nut 5, and nut 5 due to the rotation of ball screw 6 performs reciprocating traverse motion along guide shaft 7. Constant-speed servo

motor 8 rotates ball screw 6 clockwise (viewed from the top of FIG. 1) via gears 8a, 6a and moves nut 4 and traverse guide 2 in the A direction at a constant speed. Constant-speed servo motor 8' also rotates ball screw 6 counterclockwise via gears 8b, 6b and moves nut 4 and traverse guide 2 in the B direction at a constant speed. At one of ball screw 6 is attached disc 9 having a number of equally spaced apart pores near its periphery. Stroke pulse generator 10 is attached to frame 11 and produces a stroke pulse P_d in proportion to the rotating angle of disc 9, i.e., in proportion to the distance of the movement of the traverse guide 2. Stroke pulse generator 10 may be a conventional photoelectric pulse generator consisting of a light source and opposing photoelectric elements, such as phototransistor, and a pulse amplifier. Since the rotating speed of ball screw 6 is constant, the stroke pulse P_d is produced at substantially definite intervals of time. Arm 12 is attached to nut 5 at the opposite side of, and at substantially horizontally to traverse guide 2. Reference-position detector 13 is attached to frame 11 at a level Lo which nearly conforms to the center level of bobbin 3. The reference-position detector 13 which detects the passage of arm 12 may be of a conventional photoelectric type detector, like a stroke pulse generator.

The driving mechanism of traverse guide 2 is illustrated below with reference to FIGS. 1 and 2. Before filament 1 is wound on bobbin 3 inserted into spindle 15, a small length of filament is usually anchored to the waist roller (not shown) below the bobbin, or taken up by the aspirator. At this moment, the traverse guide 2 is at the lower limit Ll . Then switches S_{w1} , S_{w2} , S_{w3} are closed and the initiation signal S_1 is transmitted to the control circuit 20. Initiation signal S_1 turns output a of control circuit 20 ON (output b is OFF), and drive circuit 21 is thereby operated. The servo motor 8 rotates spindle shaft 6 clockwise, and traverse guide 2 starts to move toward the A direction from the lower limit position Ll . When traverse guide 2 reaches the reference position Lo , arm 12 traverses over the detector 13, and detector 13 produces reference position signal S_d . Upon receipt of signal S_d , the control circuit 20 starts to count the numbered stroke pulses P_d transmitted from stroke pulse generator 10. After the start of counting, when the number of stroke pulses P_d received by control circuit 20 attains a setpoint value, output a of control circuit 20 is set to OFF and output b is set to ON, so that drive circuit 21 stops its operation and actuates drive circuit 21' instead. As a result, servo motor 8' rotates ball screw 6 counterclockwise, and traverse guide 2 is reversed to travel toward the B direction. Also when traverse guide 2 passes the reference position Lo , reference position signal S_d is generated causing control circuit to start again the counting of stroke pulses P_d . As the number of stroke pulses P_d counted attains the setpoint value, control circuit 20 output a is set to ON and output b is set to OFF. The traverse guide is again reversed to travel toward the A direction. The traverse guide 2 continues the reciprocating motion.

On the other hand, the control circuit 20 automatically and sequentially reduces the setpoint value for stroke pulses P_d , and hence the stroke of the traverse guide is gradually shortened, acquiring the so-called parallel wind motion. After a definite time or definite number of reversals, the control circuit 20 completes its winding by the parallel winding traverse motion. The

traverse guide 2 is then lowered down toward the B direction until it is stopped at the height of lower limit position L_l by means of lower limit position detector 14. But is desired, the traverse guide 2 may be stopped at a suitable position, e.g., just above the lower limit position L_l for a short period of time for the purpose of forming a pig tail.

Methods of sequentially reducing the setpoint value for stroke pulses P_d for determining the distance between the reference position and the reversing position of traverse guide 2 consists of the following two: one method is to reduce the setpoint value for every reverse of the traverse guide 2, and the other is to reduce the setpoint value for every generation of a clock pulse. The setpoint value can be set as a difference between the upper limit value and the initial value of the counter circuit.

The following two types of control circuits are proposed in order to perform each of the above first and second methods: control circuits which sequentially reduce the upper limit value, maintaining the initial value constant (referred to the first and third type in this invention), and control circuits which maintain the upper limit value constant and sequentially increase the initial value (referred to the second and fourth types in this invention). Control circuits of all types are discussed below.

A control circuit 20 of the first type in which the upper limit value is reduced for every reversal of the traverse guide is illustrated with reference to FIGS. 3 and 4. The control circuit comprises gate circuit 22, consisting of AND circuit 23 and R-S type flip-flop circuit (bistable multivibrator circuit) 24, stroke pulse counter circuit 25, counter circuit 26 for setting the upper limit value, coincidence discriminating circuit 27, reverse command circuit 28 consisting of a flip-flop circuit, and AND circuit 29. The flip-flop circuit 24 is set by reference position signal S_d , and is reset by the initiation signal S_1 and coincidence signal S_e . The output signal S_g is ON when the flip-flop circuit 24 is set and OFF when the flip-flop circuit 24 is reset AND circuit 23 receives, as inputs, initiation signal S_1 , output signal S_g of flip-flop circuit 24, and stroke pulses P_d .

Stroke pulse counter circuit 25 is a binary counter circuit which is cleared to zero by the initiation signal S_1 and coincidence signal, and counts the stroke pulses P_d which come through AND circuit 23 of gate circuit 22. Counter circuit 26 is provided for setting the upper limit value is a conventional binary counter circuit, and is set to the predetermined upper limit value M by the initiation signal S_1 , and reduces the upper limit value by one for every entry of coincidence pulse signal S_e . Coincidence discriminating circuit 27 produces a coincidence signal S_e when the counted value n of stroke pulse counter circuit 25 coincides with the counted value m of counter circuit 26 for setting upper limit value; the construction of which will be mentioned later in detail with reference to FIG. 5.

Reverse command circuit 28 is a T-type flip-flop circuit in which output a is set to ON by the initiation signal S_1 which enters reset terminal R and then sets output b and output a ON alternately for every receipt of coincidence signal S_e which enters trigger terminal T. Completion indicator circuit 29 is an AND circuit which, when a predetermined number N_o of traverses are completed, i.e., when the counted value m of the counter circuit 26 for setting upper limit value reaches

the determined value ($M - N_o$), produces a winding completion signal S_x .

The operation of the control circuit 20 is mentioned below in more detail by referring to the time chart of FIG. 4. When the initiation signal S_1 is turned ON, the counted value n of the stroke pulse counter circuit 25 is cleared to zero, and the counted value m of the counter circuit 26 for setting upper limit value is set to a predetermined value M . Initiation signal S_1 causes output a of reverse command circuit 28 to be ON, so that the traverse guide 2 starts to move in the A direction from the lower limit position L_l . As traverse guide 2 moves, stroke pulses P_d are generated. But since the flip-flop 24 has been reset by the initiation signal S_1 (S_g is OFF) and gate circuit 22 is closed, stroke pulses P_d are not transmitted to the counter circuit 25 and the counted value n remains zero.

When traverse guide 2 has reached the reference position L_o , the reference position signal S_d is generated, 20 and signal S_d sets flip-flop circuit 24 to change the output signal S_g to ON. Two inputs S_1 , S_g of AND circuit then become ON, causing gate circuit 22 to open, and stroke pulses P_d are transmitted to stroke pulse counter circuit 25 thereby starting the counting. The counted 25 value n of stroke pulse counter circuit 25 increases as traverse guide 2 moves in the A direction past the reference position L_o . Coincidence discrimination circuit 27 produces a coincidence signal S_e when the counted value n of stroke pulse counter circuit 25 coincides 30 with the counted value m ($=M$) of the counter circuit 26 for setting upper limit value. The coincidence signal S_e changes the state of R-S type flip-flop circuit 28 so that output a is made OFF and output b ON. The traverse guide 2, in consequence, is reversed toward the 35 B direction. Coincidence signal S_e also causes flip-flop circuit 24 to be reset so that output signal S_g is made OFF, and gate circuit 22 is closed. As a result, stroke pulse counting circuit 25 stops the counting. Coincidence signal S_e also clears the counted value n of the counter circuit 25 to ZERO. Coincidence signal S_e , in addition, reduces the counted value m of the counter circuit 26 for setting upper limit value by one with result that the value m become equal to $M - 1$. Both counter circuits 25, 26, and coincidence 40 discriminating circuit 27 will be illustrated later in more detail.

The traverse guide 2 continues to move toward the B direction, and when it reaches reference position L_o , reference position signal S_d is generated again, causing 45 gate circuit 22 to open, and the counting of stroke pulses P_d is started again. When the counted value n of stroke pulse counter circuit 25, which increases from ZERO reaches the counted value m ($= M - 1$) of the counter circuit 26 for setting upper limit value, coincidence signal S_e is generated again. The output b of the reverse command circuit 28 is made OFF and the output a is made ON, and traverse guide 2 is reversed again. Coincidence signal S_e closes gate circuit 22, and 50 clears stroke pulse counter circuit 25 to ZERO. Coincidence signal S_e then reduces the counted value m of the counter circuit 26 for setting upper limit value by one with result that the value m become equal to $M - 2$.

Control circuit 20 continues the similar operation, and the upper limit value m is reduced one by one for every reversing; the stroke of reverse guide 2 gets gradually shorter. After a predetermined number N_o of tra-

verse has been completed, completion indicating circuit 29 produces a wind completion signal S_s , causing switches S_{w1} , S_{w2} , S_{w3} to open. The winding operation by means of parallel wind traverse motion is now completed, and traverse guide 2 returns to the lower limit position L_1 .

The two counter circuits 25, 26, and coincidence discriminating circuit 27 are illustrated below with reference to FIG. 5. Stroke pulse counter 25 which increases the counted value n for every entry of an input pulse, is a conventional binary counter circuit consisting of k units of flip-flop circuits. When a signal (S_1 or S_e) is applied to reset terminals R_1 , R_2 , R_3 , ..., R_k , the state of each flip-flop (each bit), i.e., x_1 , x_2 , x_3 , ..., x_k , is ZERO, and the state of other side, i.e., $\bar{x}_1$, $\bar{x}_2$, $\bar{x}_3$, ..., $\bar{x}_k$, is ONE. In this way, in the above-mentioned counter circuit 25, the use of x_k , ..., x_3 , x_2 , x_1 as the counted value n causes the counted value n to be cleared to ZERO by the application of the reset signal, as shown in Table 1. And the value n increases by one for every entry of an input pulse to the trigger terminal T_1 .

Table 1

		n					
		x_k	x_{k-1}	$\dots$	x_3	x_2	x_1
0	0	0			0	0	0
1	0	0			0	0	1
2	0	0			0	1	0
3	0	0			0	1	1
4	0	0			1	0	0

Counter circuit 26 for setting the upper limit value, which will be set to a predetermined value which will be decremented by one for every entry of an input pulse, is also a conventional binary counter consisting of k units of flip-flop circuits. When a signal S_1 is applied to reset terminals R_1 , R_2 , R_3 , ..., R_k , the state of each bit, i.e., y_1 , y_2 , y_3 , ..., y_k , is ZERO, and the state of other side, $\bar{y}_1$, $\bar{y}_2$, $\bar{y}_3$, ..., $\bar{y}_k$, is ONE. In the counter circuit 26 comprised as mentioned above, the use of $\bar{y}_k$, ..., $\bar{y}_3$, $\bar{y}_2$, $\bar{y}_1$ as counted value m causes said counted value m , after being set to a predetermined value, to be reduced one by one for every entry of input pulse S_e to the trigger terminal T_1 . For example, to reduce the value one by one for every entry of the input pulse S_3 , with the upper limit maintained at $M = 75$ ($m = 1001011$), the complement of m , i.e., $\bar{m} = 0110100$ (see Table 1) may be set to the binary counter circuit ($k = 7$) of 7 bits, (method of setting will be mentioned later). In this way, the complement $\bar{m}$ increases one by one for every entry of input pulse, and the counted value m decreases one by one.

TABLE 2

	$\bar{y}_7$	$\bar{y}_6$	$\bar{y}_5$	$\bar{y}_4$	$\bar{y}_3$	$\bar{y}_2$	$\bar{y}_1$	$\bar{m}$					
								$\bar{y}_5$	$\bar{y}_4$	$\bar{y}_3$	$\bar{y}_2$	$\bar{y}_1$	
M=75	1	0	0	1	0	1	1	0	1	1	0	1	0
M-1=74	1	0	0	1	0	1	0	0	1	1	0	1	0
M-2=73	1	0	0	1	0	0	1	0	1	1	0	1	0
M-3=72	1	0	0	1	0	0	0	0	1	1	0	1	1
M-4=71	1	0	0	0	1	1	1	0	1	1	1	0	0

Coincidence discriminating circuit 27 is composed of a plurality of comparative circuit 30 and an AND circuit 31. Comparative circuit 30 consist of two AND circuits, and an OR circuit. Coincidence of the counted

65 Similarly,

$$H_2H_3 = (2M-3) \times \frac{D}{d}$$

$$H_3H_4 = (2M-5) \times \frac{D}{d}$$

values n and m of two counter circuits can be detected by comparing whether the state of all bits constituting the corresponding figures are identical. Whether the state of corresponding i -th bits x_i and $\bar{y}_i$ are equal or not can be determined from the equation,

$$x_i \cdot y_i + \bar{x}_i \cdot \bar{y}_i = 1 \quad (1)$$

When the result of Eq. (1) appears to be '1', the state of the corresponding i -th bits x_i and $\bar{y}_i$ are identical, and when the result appears to be '0', they are not equal.

10 The result of Eq. (1) above is represented as an output of each comparative circuit 30. AND circuit 31 produces coincidence signal S_e only when the outputs of all comparative circuits 30 are '1'.

A method of setting the counter circuit to $\bar{m} = 0110100$ consists, as shown in FIG. 5, of first sending the initiation signal S_1 to the reset terminals R_1 , R_2 , R_3 , ..., R_k ($k = 7$) of each bit, so that the states y_1 , y_2 , y_3 , ..., y_k of each bit are all '0', and then sending a delay signal S_1' composed of initiation signal S_1 , which has been delayed for a very short period of time (e.g., 0.1 sec.) through the delay circuit, to the trigger terminals T_3 , T_5 , T_6 so that the states y_3 , y_5 , y_6 of each bit are 1.

In the foregoing, with reference to the examples shown in FIGS. 3-5, we have illustrated the control circuit of the first type in which the values $x_kx_{k-1} \dots x_2x_1$ of the counted value n is increased one by one from a definite initial value (00 ... 00) for each entry of stroke pulse P_d , and the values $\bar{y}_k\bar{y}_{k-1} \dots \bar{y}_2\bar{y}_1$ of the upper limit value m is decreased one by one for every reversing. With the system of this type, however, it is also possible to use the state of each bit of the counter circuit from the opposite side. That is, the values $\bar{x}_k\bar{x}_{k-1} \dots \bar{x}_2\bar{x}_1$ of the counted value $\bar{n}$ are reduced one by one from a definite initial value (11 ... 11) for every counting of stroke pulse P_d , and the values $y_ky_{k-1} \dots y_2y_1$ of the lower limit value $\bar{m}$ is increased one by one for every reversal. As mentioned above, the control circuit according to this invention permits this to be accomplished in two ways. The circuit, however, is substantially the same.

The distance between the reference position L_0 and a position where the reverse occurs, i.e. stroke $l(mm)$ of the traverse guide is determined by pitch $D(mm/round)$ of ball screw 6, number d of pores of disc 9 (pores/round), and upper limit value m . Hence there exists a relationship,

$$l = \frac{m \times D}{d} \quad (2)$$

50 Accordingly, the first stroke H_1H_2 shown in FIG. 4. gives,

$$H_1H_2 = H_1L_0 + L_0H_2$$

$$= M \times \frac{D}{d} + (M-1) \times \frac{D}{d} = (2M-1) \times \frac{D}{d}$$

From the above, it will be understood that the stroke is shortened by $2D/d$ for every reversal. The length LoH_1 of the first half-stroke is determined by the set-point M . For example, where $D=6\text{ (mm/round)}$ and $d=30\text{ (pores/round)}$, M should be 750 to obtain $LoH_1 = 150\text{ mm}$. Therefore, where $M = 750$, the relationship $2^{10} > 750 > 2^9$ holds true, and accordingly stroke pulse counter circuit 25 and counter circuit 26 for setting upper limit value must be binary counters of at least 10 bits. The time required for the completion of winding can be found from the number of traverses. For example, if the initial upper limit is set to M , with the number of traverses required being No , the number of stroke pulses Pd produced before the completion of winding can be represented as

$$(2M-1)+(2M-3)+\dots+[2M-(2No-1)] = No(2M-No)$$

Denoting the time interval separating successive stroke pulses P_d by ΔT , the winding time T can then be given by $T = No(2M - No) \Delta T$. When the counted value m of counter circuit 26 for setting upper limit value reaches the predetermined value $M - No$, the completion command circuit 29 produces a winding completion signal S_s .

Control circuit 20 of the second type which employs the system in which the upper limit value M remains constant and the initial value increases by one for every reversal is illustrated below with reference to FIGS. 6, 7 and 8. In FIG. 6, numerals correspond to those of FIG. 3. The control circuit 20, consists of gate circuit 22 composed of AND circuit 23 and flip-flop circuit 24, stroke pulse counter circuit 25, counter circuit 26 for setting initial value, coincidence discriminating circuit 27, flip-flop circuit 28, AND circuit 29, upper limit setted circuit 33, and delay circuit 34.

The gate circuit 22, composed of AND circuit 23 and flip-flop circuit 24, is opened by the reference position signal S_d and is closed by the coincidence signal S_e . Stroke pulse counter circuit 25 is an ordinary binary counter circuit which is cleared to ZERO by the initiation signal S_i , and the delay control signal S_c' , and increases the counted value n by one for every entry of stroke pulse P_d . Upper limit setting circuit 33 is an AND circuit which produces a control signal S_c when the counted value n of stroke pulse counter circuit 25 reaches the upper limit value M (constant). The counter circuit 26 for setting initial value is an ordinary binary counter circuit which is cleared to ZERO by the rising of the initiation signal S_i , and increases the counted value m by one for every entry of control pulse signal S_c . Coincidence discriminating circuit 27 produces a coincidence signal S_e when the counted value n of the stroke pulse counter circuit 25 and the counted value m of the counter circuit 26 for setting initial values coincide. Its construction will be mentioned later with reference to FIG. 8. Reverse command circuit 28 is a T-type flip-flop circuit which is set to ON by the initiation signal S_i , and thereafter sets outputs b , a alternately ON for every entry of control pulse signal S_c from AND circuit 33. Completion command signal 29 produces a wind completion signal S_s when the predetermined number N_o of traverses is completed, i.e., when the counted value m of counter circuit 26 for setting initial value reached the predetermined value N_o . Delay circuit 34 causes delays of very short periods of time (e.g., 0.01 sec.) in order that the stroke pulse counter circuit 25 is prevented from being cleared to ZERO by control pulse signal S_c before the counted

value m of counter circuit **26** is set to ONE by the same control pulse signal S_c .

The operation of control circuit 20 of FIG. 6 is illustrated below in more detail with reference to time chart

5 of FIG. 7. When the initiation signal S_1 is set to ON, the counted values n and m of stroke pulse counter circuit 25 and counter circuit 26 for setting initial value are cleared to ZERO, causing output a of reverse command circuit 28 to be ON. Traverse guide 2 then starts
 10 to move for the lower limit position L_1 in the A direction. Since flip-flop circuit 24 has been reset and its output signal S_g is in the OFF state, gate circuit 22 is closed so that stroke pulse P_d is not transmitted to stroke pulse counter circuit 25. If traverse guide 2
 15 reaches the reference position L_0 , the reference position signal S_d is generated. Reference position signal S_d sets the flip-flop circuit 24, thereby causing its output signal S_g to be ON. Therefore, gate circuit 22 is opened, and stroke pulses P_d are transmitted to stroke
 20 pulse counter circuit 25 counting is then started.

As the counted value n of stroke pulse counter circuit 25 increases and reaches the upper limit M , all inputs of the upper limit setting circuit 33 are set to ON, producing control signal S_c . Control signal S_c changes the state of reverse command circuit 28, output a is set to OFF and output b ON. Traverse guide 2 is then reversed toward the B direction. Control signal S_c enters counter circuit 26 for setting initial value, and changes the counted value m from ZERO to ONE. Control signal S_c also enters delay circuit 34, and delay control signal S_c' causes stroke pulse counter circuit 25 to be cleared to ZERO.

35 cleared to ZERO. Development of control signal S_c causes no change to the state of flip-flop circuit 24, and gate circuit 22 remains open. Hence, stroke pulse counter circuit 25 continues the counting from the counted value $n =$ ZERO. Counting of one stroke pulse P_d makes $n =$ ONE; the counted value n of stroke pulse counter circuit 25 will be in coincidence with the counted value m of counter circuit 26 for setting initial value ($n = m = 1$). Coincidence discriminating circuit 27, therefore, produces coincidence signal S_e . Coincidence signal S_e resets flip-flop 24, rendering its output signal S_g OFF. Gate circuit 22, therefore, is closed, and stroke pulse 40 P_d is not transmitted to stroke pulse counter circuit 25, so that the counted value n of counter circuit 25 which has now stopped the counting is maintained at ONE. When transverse guide 2, moving in the B direction, reaches the reference position L_0 , the reference position signal S_d is generated setting the output signal S_g of flip-flop 24 ON to open gate circuit 22. As a result, the stroke pulse counter circuit 25 again starts the counting from $n =$ ONE. As the counted value n increases and reaches the predetermined upper limit value M (constant), i.e., if $M - 1$ units of stroke pulses P_d are counted, AND circuit 33 generates a control signal S_c . Control signal S_c changes output b of reverse command circuit 28 to OFF and output a to ON, and 45 causes transverse guide 2 to be reversed toward the A direction. Control signal S_c , furthermore, changes the counted value m of counter circuit 26 for setting initial value from ONE to TWO. Delay control signal S_c' clears the stroke pulse counter circuit to ZERO. Stroke pulse counter circuit 25 continues the counting, and when $n =$ TWO is obtained, coincidence discriminating circuit 27 produces a coincidence signal S_e . Coincidence signal S_e closes gate circuit 22, and maintains the 50

55

60

65

counted value n of stroke pulse counter circuit 25 which has now stopped the counting to TWO. Control circuit 20 repeats the similar operation; initial value m increases by one for every reversal, and the setpoint value (i.e., upper limit value minus initial value) decreases by one correspondingly so that the stroke of traverse guide 2 is shortened gradually. When a predetermined number N_0 of traverses is completed, completion indicating circuit 29 produces a wind completion signal S_s , and switches S_{w_1} , S_{w_2} , S_{w_3} are opened, completing the winding operation. Setting the length of initial stroke and the estimation of time required for winding can be done as in the case of control circuit 20 of the first type (FIGS. 3, 4, and 5). The two counter circuits 25, 26 and coincidence discriminating circuit in the control circuit (FIG. 6) of the second type are illustrated in FIG. 8 in detail, and depend for their operation on the same principle as those shown in FIG. 5. Stroke pulse counter circuit 25 and counter circuit 26 for setting initial value are ordinary binary circuits which increase the counted values (n, m) by one for each input pulse. For example, if the counter circuit 26 is a binary counter circuit having 7 bits, the counted value m ($y_7, y_6, y_5, y_4, y_3, y_2, y_1$) for each input pulse (S_e) will change as shown in Table 3 below.

25

30

Table 3

m						
y_7	y_6	y_5	y_4	y_3	y_2	y_1
0	0	0	0	0	0	0
0	0	0	0	0	0	1
0	0	0	0	0	1	0
0	0	0	0	0	1	1
0	0	0	0	1	0	0

The counted value n ($x_7, x_6, x_5, x_4, x_3, x_2, x_1$) of the stroke pulse counter circuit 25 also changes in the same way as shown in Table 3 in response to the entry of input pulse (P_d). Coincidence of the counted values n and m can be detected by the coincidence discriminating circuit 27, consisting of a plurality of comparative circuits 30 and an AND circuit 31. Whether the state of i -th bits x_i, y_i corresponding to both counter circuits 25, 26 are equal or not can be determined from the equation,

$$x_i \cdot y_i + \bar{x}_i \cdot \bar{y}_i \quad (2)$$

The result of Eq. (2) can be represented as an output of the comparative circuit 30 composed of two AND circuits and one OR circuit. When the state of all bits corresponding to both counter circuits are equal, the outputs of all comparative circuits 30 will be 1 and AND circuit 31 will produce a coincidence signal S_e .

In the foregoing, with reference to examples of FIGS. 6-8, we have illustrated a control circuit of the second type in which the values $x_k x_{k-1} \dots x_2 x_1$ of the counted value n are increased one by one for every entry of stroke pulse, and the values $y_k y_{k-1} \dots y_2 y_1$ of the counted value m are increased one by one for every entry of the coincidence signal S_e . With the system of this type, however, it is possible to express the value in the following way by using the state of each bit of the counter circuit from the opposite side. That is, the value $\bar{x}_k \bar{x}_{k-1} \dots \bar{x}_2 \bar{x}_1$ of the counted value n is decreased by one for every entry of stroke pulse, and the value $\bar{y}_k \bar{y}_{k-1} \dots \bar{y}_2 \bar{y}_1$ of the counted value m is decreased by one for every entry of the coincidence signal S_e . In this way, the control circuits of systems in accordance with this invention can express the values in two ways. But

35

30

35

40

45

60

65

since the circuits are substantially the same, the description hereinafter will proceed with the former expression method.

If now $M = 75$ (1001011), the purpose of the AND circuit constituting the upper limit setting circuit 33 in FIG. 6, can be achieved by applying the state x_7, x_4, x_2, x_1 of bits of stroke pulse counter circuit 25 as an input. The AND circuit, of course, may be applied with the state of $x_7, \bar{x}_6, \bar{x}_5, x_4, \bar{x}_3, x_2, x_1$ of each bit as an input.

The tapered portion of the package formed by control circuits 20 of the above first and second types which reduce the stroke by a definite length for every reversal, acquires a curve of somewhat convex-shape. This results from a constant filament feeding speed and a constant traveling speed of the traverse guide, wherein the ratio of package diameter increasing per stroke is on the decrease with the increase of package diameter, while maintaining a constantly decreasing ratio of stroke. The form of tapered portion can be analyzed as follows:

$$\left\{ \begin{array}{l} l(n) = l_0 - n \Delta l \\ r(n) = r_0 + \frac{n}{\Delta r} \Delta r \\ T(n) = \frac{l(n)}{v_0} \\ \Delta r = \frac{w_0 T(n)}{2\pi r(n) l(n)} \times \Delta D \end{array} \right.$$

where,

n is the number of traverse,
 $l(n)$ is the length of a half-stroke of the n -th traverse,
 l_0 is the length of a half-stroke of the first traverse,
 Δl is the amount by which the stroke reducer driving each reversal,

$r(n)$ is the radius driving package of the n -th traverse,
 r_0 is the radius of bobbin,
 Δr is the amount of package radius which by which the package radius increases during each traverse,
 $T(n)$ is the time required for a half-stroke at the n -th traverse,

v_0 is the traverse speed (constant),
 w_0 is the filament feeding speed (constant),
 ΔD is the amount by which the radius increases per winding.

From the above, we obtain a relationship,

$$l = - \frac{2\pi v_0 \Delta l}{w_0 \Delta D} (r - \frac{1}{2} v_0) + \frac{\pi v_0 \Delta l r^2}{2 w_0 \Delta D} + l_0 \quad (3)$$

From Eq. (3) above, it will be understood that the tapered portion of the package acquires a parabola shape. This conforms to the fact that the tapered portion acquires the curve of somewhat convex-shape. Selecting the parameters of Eq. (3) above appropriately, it is possible to vary the form (inclination, etc.) of the tapered portion. Usually, the inclination of the tapered portion can be adjusted by changing the amount Δl by which the stroke is reduced for every reversal. To change Δl , for example, the number d of pores of disc 9 may be changed.

As methods for reducing the setpoint by changing the upper limit value or the initial value, we have so far

lustrated control circuits of the first and second types which make use of pulse (S_e) produced at the time of reversing. We should now mention the control circuits of the third and fourth types, employing a system which reduces the setpoint value for every definite interval of time using a clock pulse. This method can be classified to the third type control of circuit which reduces the upper limit value while maintaining the initial value at constant (ZERO) and the fourth type control circuit which increases the initial value maintaining the upper limit value constant.

First, the third type of control circuit employing a method of reducing the upper limit value using a clock pulse is illustrated below with reference to FIGS. 9 and 10. The third type of control circuit 20 is constructed in the same manner as the control circuit 20 shown in FIG. 3, except for the inclusion of clock pulse generator 36 and clock gate circuit 37, and operates in a slightly different manner that the counted value m of the counter circuit 26 for setting upper limit value is decreased by one for each clock pulse P_t . Clock pulse generator circuit 36 is a conventional pulse generator circuit which de-multiplies the pulse produced by the astable multi-vibrator in order to produce clock pulses P_t for every interval of time τ (constant). Clock gate circuit 37 is an AND circuit which receives, as inputs, an initiation signal S_1 and clock pulses P_t . Other elements correspond to those shown in FIG. 3 (indicated by same numerals). The operation of the third type of control circuit 20 shown in FIG. 9 is as diagrammed in the time chart of FIG. 10. The operation of the first type control circuit (FIG. 4) is equal to the operation of the third type control circuit except in the method of chaning the upper limit value m . According to the first type of control circuit, the upper limit value m is reduced by one by a coincidence signal S_e which will be produced simultaneously with the reversal of the traverse member, whereas the counted value m of the third type of control circuit 20 is reduced by one for every production of clock pulse P_t .

If the time interval τ of clock pulses P_t is made nearly equal to the time required for the initial traverse (H_1H_2) as shown in FIG. 10, a clock pulse P_t is generated for every traverse (H_1H_2 , H_2H_3 , H_3H_4), and the upper limit value m is reduced by one. But as the time required for the traverse gets shorter and shorter, no clock pulse P_t is generated during the traverse of H_4H_5 . Hence there exists a relation $LoH_4 = LoH_5$. For example, in FIG. 10, if it is assumed, where $m = M = 50$ that the time interval τ of clock pulse P_t is 100 times when the interval τT at which stroke pulse P_d is generated, as well as if the initial clock pulse P_1 is generated at the time of $n = 27$, then the upper limit m will be 49 on account of clock pulse P_1 . The traverse memebor is reversed when the counted value n reached $n = 49$, and hence the next clock pulse P_2 will be generated when

$$n = 100 = [(49 - 27) + 49] = 29$$

That is, the next clock pulse P_2 will be generated when 29 units of stroke pulses are produced after the reference position Lo of the next traverse H_1H_2 has been passed. The upper limit value m will then be $m = 48$. In the same way, P_3 is produced between traverse H_2H_3 when $n = 100 - [(48 - 29) + 48] = 33$, so that $m = 47$, and accordingly P_4 will be generated between traverse H_3H_4 when $n = 100 - [(47 - 33)] + 47 = 39$, so that $m = 46$. The next clock pulse P_5 will not be produced between traverse H_4H_5 because $100 - [(46 - 39) + 46] =$

$47 > 46 = m$, but will be produced when a stroke pulse P_d is produced after the reverse of the traverse member. Similarly, P_6 will be produced with 10 pulses P_d are generated after the traverse member has been reversed.

Practically, however, the upper limit values m are far greater than the above illustrated examples, and the ratios of the time interval τ of clock pulses P_t to the time interval ΔT at which stroke pulse P_d are generated are far greater than those shown above. But the principle 10 is quite the same.

As mentioned above, the third type of control circuit 20 reduces the upper limit value m by one for every definite interval of time τ in order that the traverse guide 2 assumes the reciprocating motion of which stroke becomes gradually shorter.

Next, we should illustrate the fourth type of control circuit 20, employing a system in which the initial value increases for every definite period of time using a clock pulse, with reference to FIGS. 11 and 12. The fourth type of control circuit 20 is constructed in the same manner as the control circuit 20 FIG. 6 of the second type, except for the inclusion of a clock pulse generator 36, clock gate circuit 37, monostable multivibrator 40, and auxiliary gate circuit 39 consisting of AND circuit 41. Delay circuit 34 contained in the second type control circuit 20 is not needed here, and hence it is omitted.

The clock pulse generator 36 produces a clock pulse P_t for every definite period of time τ (constant) in the 30 same way as produced by the third type of control circuit 20 (FIG. 9); the counted value m of the circuit 26 for setting initial value starts from ZERO and increases by one for each clock pulse P_t . The auxiliary gate circuit 39 consisting of monostable multivibrator 40 and 35 AND circuit 41, works to block the coincidence signal S_e for a very short period of time just after the production of reference position signal S_d for the purpose of preventing the gate circuit 22 from being closed just after the production of the reference position signal S_d .

The operation of the fourth type of control circuit 20, 40 shown in FIG. 11, is as diagrammed in the time chart of FIG. 12. The operation of the fourth type of control circuit is identical to the second type of control circuit (FIG. 7), except for the method of changing the initial 45 value. With the second type control circuit, the counted value m of the counter circuit 26 for setting initial value increases by one for each control signal S_c produced simultaneously with the reversing, whereas with the fourth type of control circuit 20, the counted value m increases by one for every production of clock pulse P_t . Briefly illustrating the operation of the fourth type of control circuit 20, if the time interval of clock pulse P_t is allowed to be equal to the time required for the initial traverse (H_1H_2) as shown in FIG. 12, then a clock pulse P_t will be produced for every traverse (H_1H_2 , H_2H_3 , H_3H_4) and the counted value m of the counter circuit 26 will be increased by one each time. However, the periods required for the traverse, which 50 is on the decrease, will not allow the production of a clock pulse during the traverse of H_4H_5 , leaving the counted value m maintained at 4. Hence a relation $LoH_5 = LoH_6$ holds. In FIG. 12, if a clock pulse P_6 is produced while the counted value n of the stroke pulse counter circuit is maintained at $n = 5$, the counted 55 value m of the counter circuit 26 will increase by one to become $m = 6$. When the reference position signal S_d is generated, the counting of stroke pulse counter

60

65

circuit 26 is started again, and when the counted value n is increased by one to become $n = 6$, a coincidence signal S_e is produced. In this instance, however, due to the operation of the gate circuit 29, composed of monostable multivibrator 40 and AND circuit 41, coincidence signal S_e will be blocked and corrected coincidence signal S_e' is not allowed to become ON. The control circuit 20 in the same way reduces the upper limit value m by one for each definite interval of time τ so that the stroke of traverse guide 2 shortens gradually.

With the third and fourth types of control circuits 20, the time required for completing the winding can be set precisely by the counter circuit 26 for setting upper limit value (or initial value). That is, if the reciprocating motion is completed when the upper value (or initial value) reaches the predetermined number $M - N_0$ (or N_0), then the time required for winding will be $N_0 \times \tau$.

Consideration should now be directed to the shape of the package formed by the control circuits 20 of the above-mentioned third and fourth types according to which the setpoint is reduced by one for each definite interval of time τ so that the stroke is reduced by a definite length each time. With this method, the tapered portion of the package is substantially linear and not curved. This is desirable for increasing the stability of the package. The following reasons may presumably be causes that the tapered portion acquires a linear shape. The rate of frequency of reversing direction responsive to the production of clock pulse P_t (varies with shortening stroke) increases with the increase of diameter due to the continuing reciprocal motion. Also the rate of increase of the diameter during one stroke decreases with the increase of diameter. These factors compensate or offset each other so that the amount of diameter increased compared to the amount of stroke decreased are nearly equal.

The shape of the tapered portion can be analyzed as follows:

$$\left\{ \begin{array}{l} l(t) = l_0 - \frac{t}{\tau} \Delta l \\ r(t) = r_0 + \int_0^t \Delta r \, dt \\ \Delta r = \frac{w_0}{2\pi r(t)} \times \Delta D \end{array} \right.$$

where,

t is time,

$l(t)$ is the length of a half-stroke of traverse,

l_0 is the length of a half-stroke of the initial traverse (about 0.2 m),

τ is the time interval of clock pulse P_t (about 24 sec),

Δl is the amount of half-stroke reducing for every production of clock pulse P_t (about 0.2×10^{-3} m),

$r(t)$ is the radius of package,

r_0 is the radius of bobbin (about 0.025 m),

Δr is the rate by which the package radius increases per unit time,

w_0 is the filament feeding speed (about 45 m/sec),

ΔD is the amount of radius increasing per winding (about 0.1×10^{-3} m),

Values in parenthesis denote those used in embodiments. From the above, we obtain a relationship,

$$l = l_0 \exp \left\{ - \frac{2\pi\Delta l}{w_0\tau\Delta D} (r - r_0) \right\} \quad (4)$$

From Eq. (4), it will be understood that the shape of the tapered portion of package is in the form of an exponential curve. Since $\{ -[(2\pi\Delta l)/(w_0\tau\Delta D)](r - r_0) \}$ is sufficiently less than 1, Eq. (4) can be approximated to

$$l - l_0 \approx - \frac{2\pi l_0 \Delta l}{w_0 \tau \Delta D} (r - r_0) \quad (5)$$

As will be understood from Eq. (5), the tapered portion of package takes the form of a substantial straight line. 20 Also, appropriately selecting the parameters of Eq. (5) above, it is possible to freely determine the inclination of the tapered portion. Usually, inclination of the tapered portion, i.e., the rate of stroke length l decreasing with the increase of radius r , can be adjusted by changing the time interval τ of clock pulse P_t .

The foregoing dealt with the control devices of the four types used for controlling the yarn guide members of this invention. Also, in the description of the counter circuits, if the conditions for each bit and the binary relationship between 1 and 0 are specified in opposite order, the expression "the counted value increases by one" can be replaced by "the counted value decreases by one." Accordingly, it should be taken that the expression, the counted value increases (decreases), merely specifies the relationship between the two counter circuit (25, 26). And it will be clear that these control devices are also applicable to the instances where the ring of the ring twister is being reciprocated, as well as the instances where the spindle of the Flyer-type twister is being reciprocated.

It should also be understood that the setups of the control circuit in accordance with this invention make it possible to provide a variety of modifications. For example, the stroke pulse counter circuit 25 which starts the counting with the production of the reference position signal S_d , may be made to start the counting after certain periods have passed from the time of the production of the signal S_d . Since the traverse speed is always constant, the stroke of all traverse is merely lengthened by a definite length. Also, FIG. 1 shows a rod-like arm 12 of which width is negligible, but the arm of a definite width may be used instead. In this case, the reference position signal S_d assumes a rectangular wave of a definite width. And if the counting of stroke pulses is started from the instant of rising (OFF to ON) of the reference position signal S_d , the length of the stroke will be shorter by the width of arm compared to the instance where a rod-like arm is used. Conversely, if the counting of stroke pulses is started from the instant at which the signal S_d is turned to OFF, the length of the stroke is lengthened by the width of arm. Furthermore, a delay circuit, which upon receipt of a command of reverse from the control circuit effects the reversing after certain periods have passed, 55 may be used. In this way, it will be understood that the use of a variety of "Delay" makes it possible to reduce the number of bits in counter circuit 25 and 26.

In the foregoing, the present invention was illustrated with reference to control circuits of four types, but it should be understood that this invention is not limited to the examples disclosed and shown in the specification and drawings but should be regarded that all possible modifications covered by claims belong to the scope of this invention.

What we claim is:

1. A method of controlling the traverse member of winders in parallel winding, comprising the steps of: producing pulses every time the traverse member moves a predetermined distance;

defining a reference position along the path of the traverse member;

counting the number of said pulses from the time at which said traverse member has passed the reference position;

reversing said traverse member when the number of pulses counted has reached a predetermined set-point value; and,

reducing said setpoint sequentially whereby the stroke of said traverse member becomes progressively smaller.

2. A method as set forth in claim 1 wherein said set-point value is reduced sequentially for every definite numbers of reversing of said traverse member.

3. A method as set forth in claim 1 wherein said set-point value is reduced sequentially for every definite interval of time.

4. An apparatus for controlling the traverse member winders in parallel winding comprising:

a means for producing stroke pulses every time the traverse member moves a predetermined distance; a means for producing a reference position signal when said traverse member has passed a predetermined reference position;

a first counter circuit operatively coupled to said reference producing means which starts to count said stroke pulses from the time at which said reference position signal is produced and successively increases the counted value by one;

a second counter circuit operatively coupled and which counts the reversing of said traverse member and successively reduces by one the counted value which has been preset;

a coincidence discriminating circuit operatively coupled to said first and second counter circuits and which produces a coincidence signal when the counted values of said first and second counter circuits coincide with each other; and

a circuit operatively coupled to said coincidence discriminating circuit and which upon receipt of said coincidence signal causes said traverse member to be reversed, whereby the stroke of said traverse member is shortened by a definite length for every reversing.

5. A control apparatus as set forth in claim 4, wherein the second counter circuit for counting the reversing of said traverse member counts said coincidence signal.

6. A control apparatus as set forth in claim 4, wherein said first and second counter circuits consist of a binary counter circuit, said coincidence discriminating circuit consists of a plurality of comparative circuits and an AND circuit which receives as inputs outputs of said comparative circuits, and said comparative circuits being connected to the figures corresponding to both counter circuits and when the state of bits constituting

respective figures are x_1, y_1 , said comparative circuits constitute a logical circuit producing an output of $x_1y_1 + x_1y_1$, and output signal of said AND circuit being used as a coincidence signal.

5. A control apparatus as set forth in claim 4, wherein the circuit for reversing the traverse member has a flip-flop circuit which will be triggered by said coincidence signal.

8. An apparatus as set forth in claim 7, wherein said 10 winder comprises: a spindle in which is inserted a bobbin, a ball screw which has been positioned in parallel with said spindle and will change its rotating direction responsive to the output signal of said flip-flop circuit, a fixed frame to support said ball screw, a nut fastened

15 to said ball screw, a guide shaft capable of moving in the axial direction of said ball screw without rotating said nut, a traverse member attached to said nut, means for producing said stroke pulses in proportion to the rotating angle of said ball screw, and a position detector 20 which produces said reference position signal when said nut came near the center of said ball screw.

9. An apparatus as set forth in claim 8, wherein said traverse member is a guide to engage with filaments.

10. An apparatus as set forth in claim 8, wherein said 25 traverse member is a ring of a ring twister.

11. An apparatus as set forth in claim 8, wherein said ball screw is actuated by two servo motors, one servo motor being started when one output of said flip-flop circuit is made ON, thereby rotating said ball screw in the clockwise direction via a gear at a constant speed, and the other servo motor is started when the other output of said flip-flop circuit is made ON, thereby rotating said ball screw in the counterclockwise direction via a gear at the same constant speed as said speed in 35 the clockwise direction.

12. An apparatus as set forth in claim 8, wherein means which produces said stroke pulses comprises a disc attached to an end of the ball screw, said disc having, on its periphery, portions which permit the passage of light and portions which do not permit the passage of light arranged alternately and maintaining an equally spaced-apart relation, and a light source and a photoelectric element provided on said frame in such a manner as to face each other with the peripheral portion of said disc sandwiched therebetween.

13. An apparatus as set forth in claim 8, wherein said 40 position detector consists of a light source and a photoelectric element provided on said frame in such a manner as to face each other, and is actuated by the arm attached to said nut.

14. A control apparatus as set forth in claim 4, further comprising a gate circuit operatively coupled and which will be opened by said reference position signal and will be closed by said coincidence signal, said first 45 counter circuit counting stroke pulses which have passed through said gate circuit, and the counted value of said first counter circuit being cleared to zero by said coincidence signal.

15. An apparatus for controlling the traverse member 50 of winders in parallel windings, comprising:

means for producing stroke pulses every time the traverse member moves a predetermined distance; a means for producing a reference position signal when said traverse member has passed a predetermined reference position;

a first counter operatively coupled to said reference producing means and which upon receipt of said

control signal causes said traverse member to be reversed; a second counter circuit which counts the reversing of said traverse member and sequentially increases the counted value by one; and a coincidence discriminating circuit operatively coupled to said first and second counter circuits and which produces a coincidence signal when the counted values of said first and second counter circuits coincide with each other, said coincidence signal causing first counter circuit to stop the counting of said stroke pulses, whereby the stroke of said traverse member is shortened by a definite length for ever reversing.

16. A control apparatus as set forth in claim 15 wherein the second counter circuit for counting the reversing of said traverse member counts said control signal.

17. A control apparatus as set forth in claim 15, wherein said first and second counter circuits consist of a binary counter circuit, said coincidence discriminating circuit consists of a plurality of comparative circuits and an AND circuit which receives as inputs outputs of said comparative circuits, said comparative circuits being connected to the corresponding figures of both counter circuits and when the state of bits constituting the respective figures are x_i, y_i , said comparative circuits constitute a logical circuit producing an output of $x_i y_i + x_i y_i$, and the output of said AND circuit being used as a coincidence signal.

18. A control apparatus as set forth in claim 17, wherein the circuit which produces a control signal is an AND circuit connected to each bit of said first counter circuit in such a manner that all inputs are 1 only when the counted value of the first counter circuit is equal to the predetermined value.

19. A control apparatus as set forth in claim 15, further comprising a gate circuit operatively coupled and which will be opened by said reference position signal and will be closed by said coincidence signal, said first counter circuit counting stroke pulses which have passed through said gate circuit, and the counted value of said first counter circuit being cleared to zero by said control signal.

20. A control apparatus as set forth in claim 15, wherein the circuit for reversing the traverse member has a flip-flop circuit which will be triggered by said control signal.

21. An apparatus as set forth in claim 20, wherein said winder comprises;

a spindle in which is inserted a bobbin, a ball screw which has been positioned in parallel with said spindle and will change its rotating direction responsive to the output signal of said flip-flop circuit, a fixed frame to support said ball screw, a nut fastened to said ball screw, a guide shaft capable of moving in the axial direction of said nut, a means for producing said stroke pulses in proportion to the rotating angle of said ball screw, and a position detector which produces said reference position signal when said nut comes near the center of said ball screw.

22. An apparatus as set forth in claim 20, wherein said traverse member is a guide to engage with filaments.

23. An apparatus as set forth in claim 20, wherein said traverse member is a ring of a ring twister.

24. An apparatus as set forth in claim 20, wherein said ball screw is actuated by two servo motors, one servo motor being started when one output of said flip-flop circuit is turned ON, thereby rotating said ball screw in the clockwise direction via a gear at a constant speed, and the other servo motor being started when the other output of said flip-flop circuit is turned ON, thereby rotating said ball screw in the counterclockwise direction via a gear at the same constant speed as said speed in the clockwise direction.

25. An apparatus as set forth in claim 20, wherein means which produces said stroke pulses comprises a disc attached to an end of the ball screw, said disc having, on its periphery, portions which permit the passage of light and portions which do not permit the passage of light arranged alternately and maintaining an equally spaced-apart relation, and a light source and a photoelectric element provided on said frame in such a manner as to face each other with the peripheral portion of said disc sandwiched therebetween.

26. An apparatus as set forth in claim 20, wherein said position detector consists of a light source and a photoelectric element provided on said frame in such a manner as to face each other, and is actuated by the arm attached to said nut.

27. An apparatus for controlling the traverse member of winders in parallel winding, comprising:

means for producing a stroke pulse every time the traverse member moves a predetermined distance; a means for producing a reference position signal when said traverse member has passed a predetermined reference position;

a first counter circuit operatively coupled to said reference producing means and which starts to count said stroke pulses from the time at which said reference position signal is produced and sequentially increases the counted values by one;

a pulse generator circuit for producing clock pulses; a second counter circuit coupled to said pulse generator which counts said clock pulses and successively reduces by one the counted value which has been preset;

a coincidence discriminating circuit coupled to said first and second counting circuits for producing a coincidence signal when the counted values of said first and second counter circuits coincide with each other; and

a circuit operatively coupled to said coincidence discriminating circuit and which upon receipt of said coincidence signal causes said traverse member to be reversed, thereby the stroke of said traverse member being shortened by a definite length for every production of said clock pulse.

28. A control apparatus as set forth in claim 27, further comprising a gate circuit operatively coupled and which will be opened by said reference position signal and will be closed by said coincidence signal, said first counter circuit counting stroke pulses which have passed through said gate circuits, and the counted value of said first counter circuit being cleared to zero by said coincidence signal.

29. A control apparatus as set forth in claim 27, wherein said first and second counter circuits consist of a binary counter circuit, said coincidence discriminating circuit consists of a plurality of comparative circuits and an AND circuit which receives as inputs outputs of

said comparative circuits, said comparative circuits being connected to the figures corresponding to both counter circuits and when the state of bits constituting respective figures are $x_i, \bar{y}_i$, said comparative circuits constitute a logical circuit producing an output of $x_i\bar{y}_i + x_i\bar{y}_i$, and output signal of said AND circuit being used as a coincidence signal.

30. A control apparatus as set forth in claim 27, wherein the circuit for reversing the traverse member has a flip-flop circuit which will be triggered by said coincidence signal. 10

31. An apparatus as set forth in claim 30, wherein said winder comprises:

a spindle in which is inserted a bobbin, a ball screw which has been positioned in parallel with said spindle and will change its rotating direction responsive to the output signal of said flip-flop circuit, a fixed frame to support said ball screw, a nut fastened to said ball screw, a guide shaft capable of moving in the axial direction of said ball screw without rotating said nut, a traverse member attached to said nut, a means for producing said stroke pulses in proportion to the rotating angle of said ball screw, and a position detector which produces said reference position signal when said nut comes near the center of said ball screw. 15

32. An apparatus as set forth in claim 30, wherein said traverse member is a guide to engage with filaments.

33. An apparatus as set forth in claim 30, wherein said traverse member is a ring of a ring twister.

34. An apparatus as set forth in claim 30, wherein said ball screw is actuated by two servo motors, one servo motor being started when one output of said flip-flop circuit is turned ON, thereby rotating said ball screw in the clockwise direction via a gear at a constant speed, the other servo motor being started when the other output of said flip-flop circuit is turned ON, thereby rotating said ball screw in the counterclockwise direction via a gear at the same constant speed as said speed in the clockwise direction. 20

35. An apparatus as set forth in claim 30, wherein means which produces said stroke pulses comprises a disc attached to an end of the ball screw, said disc having, on its periphery, portions which permit the passage of light and portions which do not permit the passage of light arranged alternately and maintaining an equally spaced-apart relation, and a light source and a photoelectric element provided on said frame in such a manner as to face each other with the peripheral portion of said disc sandwiched therebetween. 25

36. An apparatus as set forth in claim 30, wherein said position detector consists of a light source and a photoelectric element on said frame in such a manner as to face each other, and is actuated by the arm attached to said nut.

37. An apparatus for controlling the traverse member of winders in parallel winding, comprising:

a means for producing stroke pulses every time the traverse member moves a predetermined distance; a means for producing a reference position signal when said traverse member has passed a predetermined position; a first counter circuit which starts to count said stroke pulses from the time at which said reference position signal is produced and successively increases the counted value by one; 65

a circuit operatively coupled to said first counter circuit for producing a control signal when the counted value of said first counter circuit has reached a predetermined value;

a circuit coupled to said control signal circuit which upon receipt of said control signal causes said traverse member to be reversed;

a pulse generating circuit for producing clock pulses; a second counter circuit coupled to said pulse generating circuit and which counts said clock pulses and successively increases the counted values by one; and

a coincidence discriminating circuit which produces a coincidence signal when the counted values of said first and second counter circuits coincide with each other and operatively coupled thereto, said coincidence signal causing said first counter circuit to stop the counting of said stroke pulse, thereby the stroke of said traverse member being shortened by a definite length for every production of said clock pulse.

38. A control apparatus as set forth in claim 37, further comprising an auxiliary gate circuit which will be closed by said reference position signal and will open after a very short period of time and through which said coincidence signal is sent to said first counter circuit. 25

39. A control apparatus as set forth in claim 38, wherein said first and second counter circuits consist of 30 a binary counter circuit, said coincidence discriminating circuit consists of a plurality of comparative circuits and an AND circuit which receives as inputs outputs of said comparative circuits, said comparative circuits being connected to the corresponding figures of both counter circuits and when the state of bits constituting the respective figures are x_i, y_i , said comparative circuits constitute a logical circuit producing an output of $x_i y_i + \bar{x}_i \bar{y}_i$, and the output of said AND circuit being used as a coincidence signal. 35

40. A control apparatus as set forth in claim 39, wherein the circuit which produces a control signal is an AND circuit connected to each bit of said first counter circuit in such a manner that all inputs are 1 only when the counted value of the first counter circuit is equal to the predetermined value. 40

41. A control apparatus as set forth in claim 38, further comprising a gate circuit which will be opened by said reference position signal and will be closed by said coincidence signal, said first counter circuit counting stroke pulses which have passed through said gate circuit, and the counted value of said first counter circuit being cleared to zero by said control signal. 50

42. A control apparatus as set forth in claim 38, wherein the circuit for reversing the traverse member has a flip-flop circuit which will be triggered by said control signal. 55

43. An apparatus as set forth in claim 42, wherein said winder comprises;

a spindle in which is inserted a bobbin, a ball screw which has been positioned in parallel with said spindle and will change its rotating direction responsive to the output signal of said flip-flop circuit, a fixed frame to support said ball screw, a nut fastened to said ball screw, a guide shaft capable of moving in the axial direction of said ball screw without rotating said nut, a traverse member attached to said nut, a means for producing said

stroke pulses in proportion to the rotating angle of said ball screw, and a position detector which produces said reference position signal when said nut comes near the center of said ball screw.

44. An apparatus as set forth in claim 42, wherein said traverse member is a guide to engage with filaments.

45. An apparatus as set forth in claim 42, wherein said traverse member is a ring of a ring twister.

46. An apparatus as set forth in claim 42, wherein said ball screw is actuated by two servo motors, one servo motor being started when one output of said flip-flop circuit is turned ON, thereby rotating said ball screw in the clockwise direction via a gear at a constant speed, the other servo motor being started when the other output of said flip-flop circuit is turned ON, thereby rotating said ball screw in the counterclockwise

direction via a gear at the same constant speed as said speed in the clockwise direction.

47. An apparatus as set forth in claim 42, wherein means which produces said stroke pulses comprises a disc attached to an end of the ball screw, said disc having, on its periphery, portions which permit the passage of light and portions which do not permit the passage of light arranged alternately and maintaining an equally spaced-apart relation, and a light source and photoelectric element provided on said frame in such a manner as to face each other with the peripheral portion of said disc sandwiched therbetween.

48. An apparatus as set forth in claim 42, wherein said position detector consists of a light source and a photoelectric element provided on said frame in such a manner as to face each other, and is actuated by the arm attached to said nut.
